UNITED STATES PATENT OFFICE.

THURE A. JOHNSON, OF LYNN, MASSACHUSETTS.

GARMENT HANGER.

Application filed January 29, 1925, Serial No. 5,511. Renewed August 3, 1926.

This invention relates to improvements in garment hangers and has for its principal object to provide a simple and efficient device for supporting a number of ordinary 5 coat hangers or the like, on a hanger bar, which is supported on a wall in a closet.

One of the important objects of the present invention is to provide a garment hanger of the above mentioned character, where- 10 in the same is adapted to be suspended from an ordinary clothes hook secured on a vertical wall, whereby a number of garments may be accommodated, and further permitting the device to be readily detached from 15 the supporting hook, whenever necessary.

A still further object is to provide a garment hanger of the above mentioned character, which is simple in construction, inexpensive, strong and durable, and further 20 well adapted for the purpose for which it is designated.

Other objects and advantages of this invention will become apparent during the course of the following detailed descrip- 25 tion.

In the accompanying drawing, forming a part of this specification, and in which like reference characters indicate corresponding parts throughout the several views:

30 Figure 1 is a side elevation of the garment hanger, embodying my invention, showing the manner in which the same is suspended from an ordinary clothes hook secured on a vertical wall, and

35 Figure 2 is a perspective view of the garment hanger, embodying my invention.

In the drawing, wherein for the purpose of illustration is shown the preferred embodiment of my invention, the numeral 1 40 designates generally my improved garment hanger, the same comprising a supporting block 2, the sides thereof gradually converging toward the upper edge thereof, the upper edge being slightly rounded, as clearly illustrated in Figure 2. An opening 3 is provided in the upper portion of the supporting block and provided with a means whereby the latter may be suspended from an ordinary clothes hook 4, which is secured 45 to a wall or other vertical surface 5, in the manner well known in the art.

For the purpose of holding the supporting block 2 in parallel spaced relation with respect to the wall or vertical surface 5, there

is provided on the rear face of the block, 55 at the lower portion thereof, the spacing member 6. The manner in which the spacing member 6 cooperates with the rear face of the supporting block 2 and the wall 5 is clearly illustrated in Figure 1. 60

A relatively long hanger bar, which is substantially circular in cross section, is supported, at its inner end, in suitable openings, provided therefor, in the lower portions of the supporting block 2, and 65 spacing member 6 respectively. The hanger bar, which is designated by the numeral 7 is inclined upwardly, and an enlarged ball shaped head 8 is fitted on the outer end of the hanger bar. 70

Any number of coat hangers of the ordinary construction, on which are placed the various garments to be supported may be hung on the hanger bar 7, the latter being of such length as to accommodate a number 75 of such hangers. The ball shaped head 8 and the upward inclination of the hanger bar will prevent the accidental displacement or lateral sliding movement in an outward direction, of the coat hangers from the bar. 80

The simplicity in which my device is constructed, enables the same to be readily and easily attached or detached with respect to a clothes hook, which is supported on one 85 of the walls of a closet.

While I have shown the preferred embodiment of my invention, it is to be understood that various changes in the size, shape, and arrangement of parts may be resorted to, without departing from the spirit of the invention or the scope of the appended claim. 90

Having thus described my invention, what is claimed is:

A garment hanger comprising a supporting block, the same being provided with an 95 opening in the upper portion thereof for suspending the block from an ordinary clothes hook secured on a wall, a spacing member secured on the rear face of the lower portion of the block for holding the latter in parallel spaced relation with respect to the wall, the lower portion of said block and said spacing member being provided with aligned openings, and a hanger bar having its inner end fitted in said opening. 100

In testimony whereof I affix my signature. 105

THURE A. JOHNSON.

2 sheets

Certificate of Correction.

It is hereby certified that Letters Patent No. 1,603,956, granted October 19, 1926, upon the application of Thure A. Johnson, of Lynn, Massachusetts, for an improvement in "Garment Hangers," were erroneously issued to the inventor, said "Johnson," whereas said Letters Patent should have been issued to the inventor, *said Johnson, one-third to Louis N. Gordon, and one-third to Xavier Andrew Byron, both of Lynn, Massachusetts*, assignees, as shown by the record of assignments in this office; and that the said Letters Patent should be read with this correction therein that the same may conform to the record of the case in the Patent Office.

Signed and sealed this 30th day of November, A. D. 1926.
[SEAL.]

M. J. MOORE,
Acting Commissioner of Patents.
